TABULATING MECHANISM FOR TYPE-WRITERS OR LIKE MACHINES

William H. Kupper, West Hartford, Conn., assignor to Royal Typewriter Company, Inc., New York, N. Y., a corporation of New York

Application August 21, 1950, Serial No. 180,579.

12 Claims. (Cl. 197—176)

1

This invention relates to tabulating mechanism for typewriters or like machines, and more particularly to improvements in the construction and arrangement of such mechanisms and related parts by which a complete tabulating operation can be effected by momentarily depressing a key or operating an actuating element without its being necessary to hold the key depressed or maintaining the element actuated during the tabulating "run" of the machine carriage.

In most typewriters or like machines tabulating movement of the carriage is effected by depressing a tabulating key to disable the carriage escapement mechanism and simultaneously to position a main frame mounted stop in the path of a tabular stop on the carriage, it usually being necessary for the key to be held depressed until after the carriage has completed its run and has been stopped by engagement of the carriage mounted stop with the frame mounted stop. It previously has been proposed to provide a detent or holding device for maintaining the tabulating mechanism parts in operative positions after having been set, so as to render it unnecessary to hold the key depressed throughout the whole tabulating operation. In accordance with the present invention, improved means is provided for holding the tabulating and associated parts in set or operative position after only a momentary operation of a key.

An object of the invention is to provide such a holding means which is of strong and rugged construction and capable of giving long and accurate service under the repeated shocks and strains imposed on the mechanism incident to stopping the carriage abruptly at the end of relatively long runs, when the carriage has attained considerable momentum.

Another object of the invention is to provide a mechanism of the character referred to which, although adapted for use in machines of different basic designs, is especially adapted for use to greatest advantage in power driven machines such as electric typewriters.

Another object of the invention is to provide a mechanism of the kind referred to including a novel device for preventing rebounding of the carriage after it has been stopped at the end of a tabulating run.

A further object of the invention is to provide a novel construction and arrangement of tabulating stop mechanism, tabulating brake mechanism, and escapement disabling mechanism, interconnected for operation in properly timed relation.

Other objects of the invention will become apparent from a reading of the following description, the appended claims, and the accompanying drawings, in which:

Figure 1 is a vertical, fore and aft, cross sectional view of a typewriter embodying the invention, certain parts being shown in elevation and

2

some conventional typewriter parts being omitted, the illustrated parts of a tabulating mechanism being shown in their inactive positions;

Figure 2 is a fragmentary vertical sectional view of key-operated mechanism for effecting tabulating operations, some parts being shown in elevation;

Figure 3 is a view drawn on an enlarged scale with some parts shown in vertical section substantially on the line 3—3 of Figure 1 and others in elevation, the parts being shown in their inactive positions;

Figure 4 is a view similar to Figure 3 with certain parts omitted, the parts illustrated being shown in their active or operative positions;

Figure 5 is an enlarged view, partly in elevation and partly in fore and aft vertical section, showing tabulating mechanism, a tabulating brake, and parts for operating the tabulating and brake mechanism;

Figure 6 is a fragmentary top plan view of stop parts of the tabulating mechanism shown in their normal or inactive positions;

Figure 7 is a view similar to Figure 6 but showing certain frame-mounted tabulating mechanism parts in their operative positions, and showing tabulating parts mounted on the typewriter carriage approaching the frame-mounted parts prior to arresting of the carriage in the tabulated position;

Figure 8 is a view similar to Figure 7 but showing the parts in the positions they occupy when the carriage has been arrested at the end of a tabulating movement;

Figure 9 is a detailed view, partly in elevation and partly in fore and aft vertical section, showing connections for operating the tabulating brake and frame-mounted tabulating parts;

Figure 10 is a view similar to Figure 8 but drawn on a still further enlarged scale; and

Figure 11 is a detailed view, partly in elevation and partly in section longitudinally from end to end of the machine, showing a center stop and cooperating margin stop mechanism.

The typewriting mechanism shown by way of example as embodying the invention in a preferred form is generally similar in many respects to the Royal standard office typewriter and the Royal electric typewriter. It includes a main frame element A provided with a lower track or rail 1 on which a carriage element B including end plates 2 and 3 is mounted for letter spacing and return movements by means of a carriage or top rail 4 and ball rollers, one of which is shown at 5 in Figure 1. The carriage B is equipped with the usual cylinder or platen C.

Mounted on the main frame for vertical shifting movements is a segment 6 which supports a full complement of type bars, one of which is shown at 7 pivoted as at 8 on the segment. The type bars may be operated by links, one of which is indicated at 9 which may be connected to any

suitable key operated or key controlled mechanism. Shifting of the segment for changing the case of typing may be effected by a link 10 pivoted at its upper end to the segment 6 and connected to suitable actuating mechanism, for example, mechanism of the kind disclosed in the copending application of William H. Kupper, Serial No. 133,322, filed December 16, 1949, now United States Patent No. 2,590,777, issued March 25, 1952.

The carriage B is urged to the left, that is, in the letter spacing or typing spacing direction, by suitable means such as a conventional spring drum (not shown) which exerts a steady pull on a draw band connected by a clip 11 to an ear 12 on the right hand carriage end plate 2. Movement of the carriage to the left under the urge of the spring drum or other driving mechanism is controlled by escapement mechanism illustrated partially as including a rack 13 carried by an angle bar or rail 14 having rearwardly extending arms 15 pivotally mounted on the carriage at 16. Springs 17, connected to rearwardly extending portions of the arms 15 and anchored at 18 on the carriage, normally hold the escapement rack 13 in the position shown in Figure 1, in which the rack meshes with an escapement pinion 19 journaled on a shaft 20 carried by a frame-mounted bracket 20^a. The pinion 19 is fast with an escapement wheel 21 adapted to rotate about the shaft 20 and to cooperate with escapement pawls or dogs (not shown) which may be of the kind and operated in the manner disclosed, for example, in the copending application of Henry J. Hart, Serial No. 98,738, filed June 13, 1949, now United States Patent No. 2,563,722 granted August 7, 1951.

In operation, when the escapement dog mechanism is actuated, the wheel 21 is permitted to turn in step-by-step increments so as to permit the rack 13 and, consequently, the carriage to be fed to the left in the direction of typing.

In order to limit the travel of the carriage to the left for maintaining a right hand margin on the work sheet, a margin determining center stop 22 is pivotally mounted on the frame as at 23. The center stop 22 carries a line lock lever 24 pivoted on the center stop as at 25 and having its upper end formed as a blade or finger 26 disposed in the path of a margin stop 27 mounted for adjustable positioning on a margin stop bar 28 supported on the carriage B. The lower end 29 of the line lock lever 24 is bent or otherwise extended rearwardly as at 29 or to the right in Figure 1, and is connected to a link shown partially at 30 in Figures 1, 3 and 4, which leads to parts (not shown) for locking the typing keys or otherwise preventing type bar operation when the carriage has reached a predetermined point in its travel in the letter spacing direction. A margin release key with associated mechanism (not shown) is connected by a part 31 to a push rod 32 having its forward end in contact with the rear face of a downwardly extending plate 33 secured to the center stop 22, as shown in Figure 1.

In operation, when the carriage B moves to the left to a position just short of its maximum leftward travel position, the margin stop 27 engages the blade 26 of the line lock lever 24 so as to rock the lever and push the blade 26 against the upper part of the center stop 22, thereby bringing the carriage to rest and also operating the line lock link 30 through the rocking of the line lock lever 24. If it is desired to feed the carriage a few more spaces toward the left for completing a word

or syllable, the margin release key is operated to move the part 31 and push rod 32 forwardly so as to rock the center stop 22 clockwise about its pivot 23, as shown in Figure 1, to move the upper end of the center stop 22 and the line lock blade 26 rearwardly of the margin stop 27. A limit abutment screw 27^a mounted on the right hand carriage end plate 2 is adapted to engage the line lock blade 26, even when the latter is in its margin release position, so as finally to limit the carriage travel to the left.

In accordance with the invention, a tabulating brake, which may be of known form, is cooperatively associated with tabulating mechanism for raising the carriage rack 13 to permit movement of the carriage in the typing spacing direction free of restraint by the escapement mechanism and bringing the carriage to rest at a desired tabular position, the brake serving to prevent the carriage from attaining too high a tabulating speed when long tabulating movements are performed. In the form shown, disabling of the escapement mechanism for effecting tabulating movements of the carriage is accomplished by 20 rocking of a rack bar lifting arm generally designated 34 pivoted as at 35 on the frame and having an upper arm 36 extending under the rack rail 14. The lower end of the lifting lever 34 is formed with an ear 37 (Figures 1, 5 and 9) 25 adapted to be pushed forwardly so as to rock the lever 34 clockwise as viewed in Figures 1 and 5 in a manner to be described later.

When the rack 13 is lifted and disengaged from the escapement pinion 19 by rocking of the lifting lever 34, the brake, which normally is ineffective for retarding the carriage, is brought into operation. The brake mechanism, as shown most clearly in Figure 5, includes a mounting arm 38 pivoted on the lifting lever 34 at 39 so as to have a slight movement relative to the lifting lever, limited by coaction of an opening 40 in the arm 38 and a headed pin 41 on the lifting lever 34. Normally, when the brake is inoperative, the parts will be so positioned that the pin 41 will be in engagement with the bottom of the opening 40, the arm 38 being held yieldably in this position by a spring 42 interposed between the upper arm 36 of the lifting lever 34 and an ear 38^a on the arm 38. In other respects, the brake mechanism is similar to the brake mechanism disclosed in the patent to Henry J. Hart No. 2,182,433, granted December 5, 1939. The mechanism includes a pinion 42' formed with a projection 43 adapted to engage a companion projection 44 on a brake drum 45, both the pinion 42' and the drum 45 being journaled on a stub shaft 46 carried by the brake arm 38. A spring 47 coiled around the shaft 46 normally maintains the projections 43 and 44 in the relative positions shown in Figure 5. A brake lever 48 is pivoted at 49 on the arm 38, and is formed with a shoe 50 urged into frictional engagement with the brake drum 45 by means of a spring 51 interposed between a lower extension 38^b of the arm 38 and the brake lever itself.

In operation, when the lifting lever 34 is rocked from its normal or Figure 1 position to the position shown in Figure 5, the rack 13 is moved out of engagement with the escapement pinion 19 so as to free the carriage for movement to the left unrestrained by the escapement mechanism, and, concomitantly, the arm 38 is rocked so as to bring the brake pinion 42' into mesh with the carriage rack 13. During the first part of the carriage tabulating movement to the left, the

pinion 42' will rotate substantially freely with respect to the brake drum 45, being restrained only inconsequentially by the tensioning of the light spring 47. During this initial rotation of the pinion, the projection 43 will be moving circumferentially away from the brake drum projection 44. When the pinion projection 43 engages the other side of the drum projection 44, that is, the lower face of the projection 44 as viewed in Figure 5, continued rotation of the pinion can take place only with simultaneous rotation of the brake drum 45, which is retarded frictionally by the pressure of the brake shoe 50. In this way, and as explained in more detail in the Hart Patent No. 2,182,433, referred to above, short tabulating movements of the carriage may be made without undue retarding of the carriage by the brake, whereas, if long tabulating movements are to be made, the carriage will start relatively quickly, but later will be retarded by the brake drum 45, rotation of which is resisted frictionally by the brake shoe 50.

Many of the parts described above are of known construction and relative arrangement. The invention relates more particularly to other parts to be described hereinafter, and to the arrangement of such other parts with parts already described.

The tabulating mechanism includes a support shown in Figure 5 and being generally designated 52 mounted on the carriage and comprising upper and lower rack bars 53 and 54 respectively formed with transverse grooves 55, 55 which register with each other and which are spaced longitudinally of the rack bars at letter space intervals.

Mounted on the stop frame or support 52 is a plurality of laterally settable stop devices, several of which are designated D and are shown in their normally inoperative positions, and others of which D' are shown in their rearwardly projected or operative positions. The tabular stops D—D' are similar to individual stops disclosed in the patent to Myers et al. No. 1,892,071. Each includes a bridge or central portion 57, upper legs 58 and 59, which project alongside opposite sides of the upper rack bar 53, and lower lugs 60 and 61 which project downwardly alongside opposite sides of the bottom rack bar 54. Each tabular stop part is provided with a spring 62 mounted on a pin 63, with one end hooked at 64 around the edge of the tabular stop just above the lug 60, the other end of the spring being curved as at 65 so as to press against the top rack bar 53. The arrangement is such that each tabular stop can be shifted transversely of the frame 52 to operative position at D' in Figure 5 or to an inoperative position shown at D in Figure 5, the spring 62 frictionally and yieldably maintaining the stop in whichever position it has been set.

When a tabular stop is set in its operative position as shown at D' in Figure 5, its rear edge projects toward the back of the machine sufficiently to be engaged by a frame mounted stop device adapted controllably to be moved into or out of the path of the operatively positioned stop D'. In the illustrative embodiment of the invention, the frame mounted stop device is of such construction that when it has been moved to operative position it will be set or latched in such position automatically to remain there until a tabulating operation has been completed, without its being necessary for a key or other mechanism which moved the device to operative position to be held depressed or otherwise actuated.

Thus the arrangement is such that a momentary operation of a tabular key or mechanism controlled thereby will set the frame mounted stop device in its operative position where it will remain until the tabulating operation has been completed even though the tabular key or mechanism controlled thereby is returned to its inactive or normal position before the tabulating operation has been completed.

- 10 In the form shown, the frame mounted stop device includes a tabulating lever 66 pivotally mounted at 67 on the bracket 23^a so as to be rockable about an axis parallel to the direction of carriage travel. The tabulating lever 66 is urged clockwise as viewed in Figures 1 and 5 by a spring 68 interposed between a pin 69 fixed to the lever 66 and a bracket 70 secured to the bracket 23^a. Movement of the lever 66 by the normalizing spring 68 is limited by engagement of the rear edge of the upper part of the lever with a stop ear 71 depending from a bracket 72 secured to the bracket 23^a, the stop ear 71 determining the normal or retracted position of the tabulating lever 66.
- 15 25 A flipper or blade 73 is pivotally mounted at 74 on the tabulating lever 66 so as to be rockable about an axis perpendicular to the direction of carriage travel. The blade 73 is guided in its rocking movement by a pin 75 fixed to the lever 66 and extending through a slot 76 in the blade 73. The blade is urged to rock clockwise as viewed in Figures 3 and 4 by a spring 77 interposed between a pin 78 fixed to the blade and the bracket 72. Normally, the spring 77 causes the blade 73 to press against the shank portion 79 of a latching part formed as a pin generally designated 80 mounted on the bracket 72 as shown in Figures 1, 3 and 6. The latching part 80 has a threaded part 81 which extends through a hole 82 in the bracket 72 with considerable radial clearance so as to enable the pin to be positioned adjustably and to be held in adjusted position by clamping nuts 83.
- 20 30 35 In the normal positions of the parts as shown in Figures 1, 3 and 6 the flipper blade 73 is in a retracted position, rearwardly out of the path of a projected tabular stop D' on the carriage so that the projected stop D' can pass the flipper 73 without engaging it to stop the carriage. Mechanism to be described later is provided for rocking the tabular lever 66 counterclockwise as viewed in Figures 1, 5 and 9 to move the blade or flipper 73 into the path of projected tabular stops D', the counterclockwise rocking of the lever 66 being limited by engagement of an ear 84 on the lever 66 with the back of the bracket 23^a.
- 40 45 50 55 60 When the tabular lever 66 is rocked counterclockwise from its retracted position shown in Figure 1 to its operative position shown in Figure 5, the side of the flipper blade 73 to be approached by the carriage mounted stop D' moves beyond the surface of the shank portion 79 of the pin 80 so to be disposed opposite the surface of a reduced end portion 85 on the pin 80, thereby enabling the spring 77 to swing the flipper in front of a shoulder 86 connecting the pin portions 79 and 85. Engagement of the flipper blade 73 with the shoulder 86 will latch or retain the entire frame mounted tabular stop device, including the lever 66 and blade 73, in its operative position with the blade 73 in the path of a tabular stop D' on the carriage. The latching of the frame mounted stop device in its operative position will be maintained against the returning urge of the spring 68 even though only a momentary operat-

ing impulse has been imposed on the lever 66 to move it to the operative position shown in Figure 5.

When the carriage moves in the letter spacing direction to perform a tabulating run, after disabling of the escapement mechanism, it will travel freely except as restrained by the tabulating brake, previously described, until the carriage reaches the predetermined tabular position and the operatively positioned stop D' engages the operatively positioned flipper blade 73 and moves it against the upper end of the tabulating lever 66. The parts will then be in the relative positions shown in Figure 8 so that the carriage will be arrested with the stop D' pressing to the left on the blade 73, and the latter pressing to the left against the upper end of the tabulating lever 66 which cannot move to the left because of its being supported by an upstanding part of the bracket 23^a. Movement of the blade 73 against the upper end of lever 66 will also displace the rear edge of the blade from the shoulder 86 on the pin 80, enabling the spring 68 to rock the lever 66 and the blade 73 clockwise from the position shown in Figure 5 to the normal or retracted position shown in Figure 1. This will discontinue the blocking action of the blade 73 on the stop D', but before the carriage can move to the left the escapement mechanism will be re-enabled by lowering of the escapement rack 13 into engagement with the escapement pinion 19, an operation which takes place simultaneously with movement of the blade 73 to its retracted position.

Mechanism is provided for preventing rebounding of the carriage toward the right when the carriage mounted stop D' strikes the blade 73, and the latter strikes the tabular lever 66. In the form shown, a back check or rebound preventing pawl 87 is pivoted at 88 on a bracket 89 secured to the stationary bracket 72 by screws 90. The pivot 88 includes an eccentric bushing for variably positioning the axis of rocking of the pawl 87. The pawl 87 is urged counterclockwise as viewed from above, that is as shown in Figures 6, 7, 8 and 10, by a spring 91 interposed between an upstanding ear 92 on the pawl and a fixed ear 93 on the bracket 72. The position of the pawl is determined by engagement of a finger 94 on the pawl with the pin 78 fixed to the flipper blade 73 as previously described. When the lever 66 and blade 73 are retracted so as to be in the position shown in Figure 6, the pin 78 on the flipper blade presses rearwardly against the finger 94 on the pawl 87 so as to hold the pawl in its retracted position as shown in Figure 6, with its nose disposed to the rear of the path of the tabular stop D' on the carriage. The nose of the pawl 87 has cam faces 95 and 96 engageable with the stops D' when the tabular lever 66 is projected or in operative position.

In operation, when the carriage moves to the left with a stop D' set in operative position and with the frame mounted stop device comprising the lever 66 and blade 73 being in projected position, the approaching stop D' will engage the pawl cam face 96 so as to rock the pawl 87 clockwise as viewed in Figure 6 to permit the stop D' to pass beyond the pawl nose, after which the spring 91 will rock the pawl 87 counterclockwise to the position shown in Figure 8 with the cam face 95 of the pawl disposed adjacent a tapered edge part 97 on the stop D', thereby preventing rebounding of the carriage. As soon as the blade 73 has been moved off the shoulder 86, the blade 73

and the tabular lever 66 will be returned to retracted position by the spring 68 in the manner previously described, causing the pin 78 on the blade to push rearwardly on the finger 94 of the pawl 87, thereby rocking the pawl clockwise from the position shown in Figure 8 to the position shown in Figure 6. The cam face 95 on the rebound preventing pawl 87 and the tapered face 97 on the stop D' are so related that the pawl 87 may be thus returned to its normal or inactive position without interference from the stop D' which will have moved slightly to the left, although less than a letter space, when the control of the carriage was transferred from the tabular mechanism to the escapement mechanism.

If a tabular stop D', set in operative position, should be at the left of the tabulating lever 66 when the latter is in its projected position, and if the carriage should then be returned toward the right, the tapered surface 97 on the stop D' will engage a tapered surface 73^a on the flipper blade 73 so as to cam the stop D' to its retracted or inactive position, that is the position represented by the stops D, thus permitting the carriage to return to its right hand position without being stopped by the tabulating mechanism and without damaging any of the parts.

Mechanism is provided for restoring the tabulating lever 66 to its retracted position if it should be in projected position when the margin stop 27 or the limit stop 27^a engages the center stop mechanism to stop the carriage at the end of its letter spacing travel. In the form shown, and referring particularly to Figures 1, 3 and 4, a lever 98 is pivoted at 99 on the bracket 23^a and has its lower end 100 disposed adjacent the rearwardly extending end 29 of the line-lock lever 24. The upper end of the lever 98 has a part 101 adjacent the flipper blade 73.

In operation, when the line-lock lever 24 is rocked either by the margin stop 27 or by the limiting stop 27^a as previously explained, the lower end part 29 of the line-lock lever presses against the lower end 100 of the lever 98 to rock the latter counterclockwise from the position shown in Figure 4 to the position shown in Figure 3, causing the upper part 101 of the lever 98 to press against the blade 73 and move the latter off the shoulder 86, thus enabling the spring 68 to return the lever 66 and blade 73 to their retracted positions.

Key-operated or controlled mechanism for comparatively disabling the escapement mechanism and moving the frame mounted tabular stop device 66-73 to projected position includes an operating member in the form of a pull link 102 arranged to transmit a momentary actuating effort through a cushioned drive transmitting connection generally designated 103. The connection 103 includes a three-armed lever 104 pivoted at 105 on a bracket 106 mounted by screws 107 on the rear wall 108 of the frame A. One arm 109 of the lever 104 is provided with a pivot stud 110 which mounts for rocking movements a two-armed lever 111. The lever arm 109 also has a pin 112 which extends through a hole 113 in the two-armed lever 111 with sufficient clearance to allow limited rocking of the lever 111 with respect to the lever 109. A spring 114 interposed between the arm 109 of the lever 104 and an arm 115 on the lever 111 urges the lever 111 to rock clockwise with respect to the lever 104 so as normally to be maintained in the position shown in Figure 5 in which the bottom of the hole 113

in the lever 111 engages the pin 112 on the lever 104.

Another arm 116 of the three-armed lever 104 is formed with a rounded nose 117 disposed immediately behind and being adapted to be pressed against the ear 37 previously referred to as being on the bottom of the rack bar lifting lever 34. A third arm 118 of the three-armed lever 104 is pivotally connected at 119 to the front end of a link generally designated 120, the rear end of which is pivotally connected at 121 to the lower end of the tabulating lever 66. The link 120 includes longitudinally adjustable sections 120a and 120b, relative adjustment of which is permitted by screw and slot connections indicated at 122-123.

The rear end of the pull link 102 is pivotally connected at 124 to the upper arm of the two-armed lever 111.

In operation, and beginning with the parts in their normal positions as shown in Figure 1, and with the cushion connection 103 in the condition shown in Figure 5, a tabulating run of the carriage is initiated by a momentary movement of the pull link 102 toward the front of the machine. This will tend to rock the lever 111 about its pivot 110 on the lever 103, but such rocking of the lever 111 is resisted by the spring 114. Consequently drive from the lever 111 is transmitted through the cushioning spring 114 to the three-armed lever 104, causing the latter to rock about its pivot 105, thereby causing the rounded nose 117 to press on the ear 37 to rock the rack lifting arm 34 so as to disable the escapement mechanism. Rocking of the three-armed lever 104 will also act through the link 120 to move the tabular lever 66 and flipper blade 73 to their projected positions in which they will be latched by engagement of the blade 73 with the shoulder 86 on the pin 80 as previously explained. When rocking of the three-armed lever 104 has been arrested by movement of the lifting lever 34 and the tabulating lever 66 to their limited positions the spring 114 will yield so as to enable the two-armed lever 111 to rock about its pivot 110 under the driving impulse delivered by the pull link 102, the parts of the cushioned drive transmitting connection 103 then being in the relative positions shown in Figure 9. Consequently there will be no damaging of the parts due to stoppage of movement of the lifting lever 34 and the tabulating lever 66 while the link 102 continues to move forwardly.

Inasmuch as the tabulating lever 66 and the blade 73 will be latched in their projected positions immediately upon being moved to these positions, a momentary operation followed by an immediate return of the pull link 102 will condition the parts for arresting the carriage at the end of a predetermined tabulating run without its being necessary for the tabular key to be held depressed or for the link 102 to be held in its actuated position.

The mechanism described above may be used to advantage with any suitable mechanism for delivering actuating effort to a main actuating or impulse transmitting part, e. g. the pull link 102. It can, however, be used to greatest advantage in connection with power operated actuating means, and is illustrated as being operable by a preferred form of power driven means, generally designated E. This mechanism is generally similar to but embodies improvements in mechanism disclosed in the copending application of William H. Kupper, Serial No. 6,066, filed February 3, 1948, 75

now United States Patent No. 2,567,945, granted September 18, 1951. It includes a driving element, which operates continuously, and controllable driving connections, which normally are inoperative or ineffective, but which may be conditioned by the operator to effect operative driving connection between the continuously moving driving member and the pull link 102. The driver is constituted by a continuously rotating element, more particularly a toothed snatch roll or bar 125, which may be of known form, and which is adapted to be driven in the direction of the arrow a in Figure 1 by any suitable means, but preferably by an electric motor (not shown).

The means for transmitting drive from the driver 125 to the link 102 includes an actuator 126 which extends fore and aft of the typewriter and above the member 125. The actuator 126 is pivoted as at 127 to a lever 128 at a point off-set relatively to the pivotal mounting 129 of the lever on a fixed frame cross bar 130. The actuator has a forwardly extending part 131 projecting under an abutment or guide plate 132 mounted by screws 133 on the frame A, to extend parallel to the snatch roll 125. A spring 134, interposed between the front end of the actuator 126 and an anchor plate 135, yieldably urges the actuator to rock clockwise, and thus normally maintains the actuator in the position shown in Figures 1 and 2 with its front end part 131 bearing against the abutment or guide plate 132. Another abutment 136 is disposed below the abutment 132, and is slotted to receive and guide the lower extremity of the actuator part 131 for sliding movements.

In order to apply a power impulse to the link 102, the actuator 126 is operatively but indirectly connected to the driving member 125, the actuator itself never engaging the driving member. Mechanism for bringing about the operative connection of the actuator element 126 to the member 125, includes an interponent pawl or coupler 137, pivoted as at 138 on the actuator. A spring 139, anchored to the actuator 126 and connected to the pawl part 137, biases or urges the latter to rock clockwise so as to move its nose 137a into transient engagement with the snatch roll 125. Normally, the pawl is maintained out of engagement with the snatch roll by the restraining action of a control element or trigger 140 which is pivoted as at 141 on the actuator 126. In the normal position of the trigger, its rear end 142 engages a holding surface 143 on the pawl so as to prevent the spring 139 from rocking the pawl element 137 into drive-transmitting engagement with the driving member 125. The pawl 137 is formed with an inclined resetter cam face 144 which is located just below the holding surface 143, and which is acted upon by the trigger for rocking the pawl counterclockwise, and thus resetting it in normal, inoperative position.

Operator controlled means is provided for bringing about operative driving connection between the driver 125 and the actuator 126. This means includes a manually operable tabular key 145 pivoted as at 146 on the frame A. Normally, the tabular key 145 is held in its upper position engaging a cushion stop 147.

The tabular key 145 has an upward projection 148 disposed behind an arm 149 of an operating lever 150, pivoted as at 151 on a frame-mounted cross bar 152. The lever 150 has another arm 153 on which a limber dog or flipper 154 is pivoted at 155. A spring 156 urges the limber dog 154 to rock clockwise to yieldably retain it in its normal position of rest against a limit stop

157. The dog 154 can swing counterclockwise from the position shown in Figures 1 and 2, but cannot move clockwise from this position. A returning spring 158, interposed between the tabular key 145 and a short arm 159 on the lever 150, yieldably holds the lever 150 and the tabular key 145 in their normal positions. In the normal positions of the parts, the lower end of the limber dog 154 overlies a contact ear 160 on the actuator 126.

In operation, when the tabular key 145 is depressed, the lever 150 is rocked clockwise to cause the flipper 154 to push the actuator 126 downwardly to an initial extent sufficient to bring the trigger 140 into engagement with the abutment 136. This causes the trigger to be rocked clockwise about its pivot 141, so as to release the pawl 137, which is then moved by the spring 139 into engagement with the snatch roll 125. The snatch roll then drives the pawl 137 and actuator 126 as a unit so as to rock the lever 128 and operate the link 102. When the pawl 137 is cast off from engagement with the snatch roll 125, the spring 134 lifts the actuator 126 to bring the trigger 140 into engagement with the upper, trigger-resetting abutment 132. This causes the trigger 140 to be rocked counterclockwise, so as to move its end 142 against the resetting cam face 144 of the pawl 137, thereby restoring the latter to its inactive position. The parts of the mechanism E will then be returned toward their normal positions by a spring 161 interposed between a rearwardly extending arm 162 on the lever 128 and the lower part of a bracket 163 fixed to the frame cross bar 130, the tabular lever normalizing spring 68 assisting the spring 161 after unlatching of the stop device 66-73 at the end of a tabulating run for returning the parts fully to their normal positions. The lever 128 is provided with a heel 164 engageable with the upper part of the bracket 163 for limiting the return movement of the lever 128 and the connected parts to their normal positions under the urge of the springs 161 and 68.

Means are provided for adjusting or varying the amount of driving impulse generated by the power mechanism E. This variation or adjustment is effected by variably limiting the extent to which the actuator pawl nose 137a enters a tooth interspace on the snatch roll 125 under the urge of the spring 139 when the restraint of the trigger 140 on the pawl 137 is discontinued. In the form shown, the actuator 126 is provided with a downwardly extending stop element or finger 165 which is disposed in front of and normally out of contact with a downwardly extending stop part, heel, or finger 166 on the pawl 137. When the pawl 137 is rocked clockwise by the spring 139 so as to move the pawl nose 137a into a snatch roll tooth interspace, the pawl stop 166 moves toward the actuator stop 165, which may be so positioned as to be engaged by the stop 166 to arrest rocking of the pawl 137 before the tooth 137a moves to the root of the snatch roll tooth interspace. By variably positioning one of the stops 165, 166, e. g., by bending the stop 165 towards or away from the stop 166, the extent to which the pawl tooth 137a enters the tooth interspace can be varied. Consequently, the angle through which the snatch roll rotates while in contact with the pawl, which determines the amount of driving of the pawl 137 and actuator 126 by the snatch roll 125, can be varied. Any suitable means or construction may be provided for adjusting one

of the stops 165, 166 relatively to the other, but in the preferred construction the stop 165 is formed integrally with the actuator 126 so as to be bendable toward or away from the stop 166.

5 In typewriters or like machines in which all or some of the instrumentalities to be operated, e. g., type bars, carriage return mechanism, tabulating mechanism, and escapement mechanism, are operated by power, it may be desirable to provide means for varying collectively the extent of driving of the several actuator pawls corresponding to the pawl 137 and associated with the other mechanisms referred to. This may be accomplished by providing a knock off bar 167 mounted on the main frame so as to extend under the front ends of all of the actuators corresponding to the actuator 126 shown in Figures 1 and 2. Any suitable means (not shown) may be provided for adjustably tilting or otherwise variably positioning the knock off bar 167 so that it will be engaged by the lower ends of the actuators to control the timing of disengagement of the associated actuator pawls from the snatch roll.

Operation

In order that the cooperation of the various parts and sub-mechanisms may be clearly understood, a complete and typical operating cycle will be described. In the normal positions of the parts as shown in Figures 1, 2, 3 and 6, the power driven mechanism E will be ineffective for transmitting power to the pull link 102, the escapement rack 13 will be in mesh with the escapement pinion 19 so that the carriage will be under the control of the escapement mechanism, the brake pinion 42' will be disengaged from the escapement rack 13 so that the carriage brake is disabled, and the tabulating device comprising the lever 66 and the flipper blade 73 will be retracted so that the blade 73 will be out of the path of a projected stop D' on the carriage. In order to effect a tabulating run of the carriage, the tabulating key 145 is depressed so as to rock the lever 150 and cause the flipper 154 to depress the actuator 126 until the trigger 140 is rocked by the abutment 136 so as to release the actuator pawl 137 and permit it to be moved into engagement with the snatch roll 125 by the spring 139. The pawl 137 and the actuator 126 will then be moved momentarily forwardly to pull the link 162 and transmit drive through the cushioning connection 103 so as to rock the escapement rack lift lever 34 and the frame mounted tabulating lever 66 to the positions shown in Figure 5. Rocking of the lifting lever 34 will condition the carriage brake for operation and will disengage the escapement rack 13 from the escapement pinion 19 so as to permit the carriage to perform a tabulating run under the retarding action of the brake.

The rocking of the tabulating lever 66 will move the flipper blade 73 off the shank portion 79 of the pin 80 so as to enable the spring 77 to move the blade 73 in front of the shoulder 86. The blade will then be in the position shown in Figure 7 in which both the blade and the tabulating lever 66 are latched in projected positions, with the blade 73 in the path of the stop D' on the carriage.

70 Just before completion of the tabulating run the stop D' will engage the cam face 96 on the rebound preventing pawl 87 so as to push the nose of the pawl rearwardly against the urge of the spring 91, enabling the stop D' to pass beyond the nose of the pawl 87 and to engage the

flipper blade 73, which is then pushed to the position shown in Figures 8 and 10, thus preventing further leftward movement of the carriage. By this time the spring 91 will have returned the rebound, preventing pawl 87 to the position shown in Figures 7, 8 and 10 so that the cam face 95 of the pawl will then lie adjacent the tapered face 97 of the stop D', the pawl 87 then being positioned to prevent rebounding of the carriage.

As soon as the carriage has been arrested by movement of the parts to the positions shown in Figures 8 and 10, wherein the blade 73 has moved off the pin shoulder 86, the normalizing spring 68 will rock the tabulating lever 66 to its retracted position, thereby removing the restraint of the blade 73 on the carriage stop D', and substantially simultaneously rocking the lifting lever 34 to its normal position so as to restore the carriage to the control of the escapement mechanism.

If the carriage should be moved toward its right end position when the tabulating lever 66 is in its operative or projected position and a stop D' then to the left of the tabulating lever 66 is in its set or operative position, the tapered face 97 on the stop D' will engage a tapered cam face 73a on the blade 73, causing the stop D' to be moved to its inoperative position as represented by the showing of the stops D. In this way the carriage will be permitted to continue its rightward movement without damaging the parts.

As previously has been explained it is necessary for the link 102 to act only momentarily on the escapement mechanism, the brake and the tabulating lever 66, because these mechanisms are latched in their operative positions by engagement of the blade 73 with the pin shoulder 86. Consequently it is not necessary for the tabulating key 45 to be held in depressed position throughout a tabulating run.

The mechanism disclosed for the purpose of illustrating the invention embodies the invention in a preferred form but it is intended that the disclosed mechanism be considered as illustrative rather than definitive of the invention. The invention is defined in the appended claims.

I claim:

1. In a typewriting or like machine, a frame element; a carriage element; means mounting said carriage element for travel on said frame element in mutually opposite directions; means for driving said carriage element in one of said directions; escapement mechanism for controlling said driving of said carriage element; a first stop device on one of said elements; a second stop device on the other of said elements comprising a first member and a second member separate from and mounted on said first member to move relatively thereto; means mounting said second stop device on said other of said elements to move with its said first and second members moving concurrently from a retracted position in which said second member is disposed out of line with said first stop device in the direction of carriage travel and to a projected position in which said second member is disposed in line with said first stop device in the direction of carriage travel; a latching part with respect to which said second stop device is movable; means operative upon said second member when said second stop device is moved to said projected position for moving said second member relatively to said first member and into latching

engagement with said latching part thereby to hold said second stop device in projected position, said second member being engageable with said first stop device at a predetermined position 5 of said carriage element during its travel on said frame element for moving said second member relatively to said first member and out of latching engagement with said latching part and for bringing said carriage to rest; means 10 for then returning said second stop device to its retracted position with said first and second members moving concurrently; means for disabling said escapement mechanism when said second stop device is moved to its projected position and re-enabling said escapement mechanism when said second stop device is returned to its retracted position; a first margin stop on said frame element; a second margin stop on said carriage element cooperable with said first margin stop independently of said first and second stop devices for limiting travel of said carriage element in said one of said directions, one of said margin stops being movable by the other of said margin stops; and connections between said 20 25 30 35 40 45 50 55 60 65 70 75 margin stops.

2. In a typewriting or like machine, a frame element; a carriage element; means mounting said carriage element for travel on said frame element in mutually opposite directions; means 35 for driving said carriage element in one of said directions; escapement mechanism for controlling said driving of said carriage element; a first stop device on one of said elements; a second stop device on the other of said elements comprising a lever, means mounting said lever on said other of said elements to rock about an axis parallel to the direction of carriage travel, and a blade pivotally mounted on said lever to rock about an axis perpendicular to the lever axis, rocking of said lever moving said second stop device from a retracted position in which said blade is disposed out of line with said first stop device in the direction of carriage travel and to a projected position in which said blade is disposed in line with said first stop device in the direction of carriage travel; a latching part with respect to which said second stop device is movable; spring means operative upon said blade when said second stop device is moved to said projected position for moving said blade relatively to said lever and into latching engagement with said latching part thereby to hold said second stop device in projected position, said latching part having a first portion normally engaged by said blade when said second stop device is in retracted position and another portion offset from said first portion to form a resultant shoulder extending transversely with respect to said portions, said spring means being operable when said second stop device is moved to its projected position for moving said blade against said other portion for engagement with said shoulder to latch said second stop device against returning to its retracted position, said blade being engageable with said first stop device at a predetermined position of said carriage element during its travel on said frame element for moving said blade relatively to said lever and out of latching engagement with said shoulder and for bringing said carriage to rest;

means for then returning said second stop device to its retracted position; and means for disabling said escapement mechanism when said second stop device is moved to its projected position and re-enabling said escapement mechanism when said second stop device is returned to its retracted position.

3. Typewriting or like machine mechanism as set forth in claim 2 including means for adjusting the position of said latching part relatively to the pivotal mounting of said lever.

4. Typewriting or like machine mechanism as set forth in claim 2 including means for adjusting said latching part both in the direction of carriage travel and perpendicularly to said direction.

5. In a typewriting or like machine, a frame; a carriage mounted on said frame for travel in typing spacing and return directions; means for driving said carriage in typing spacing direction; escapement mechanism for controlling said driving of said carriage; a tabular stop mounted on said carriage; a tabular stop lever pivotally mounted on said frame to rock about an axis parallel to the direction of carriage travel; a blade mounted on a side of said lever approached by said tabular stop during driving carriage travel in the typing spacing direction to rock about an axis perpendicular to the direction of carriage travel; normalizing means for holding said lever in a retracted position such that said blade is disposed out of the path of said tabular stop; actuating means for rocking said lever to a projected position such that said blade is disposed in the path of said tabular stop; a latch member mounted on said frame and extending alongside said blade on the side thereof approached by said tabular stop during carriage travel in the typing spacing direction and being formed with a first surface relatively near said lever, a second surface relatively far from said lever, and a connecting shoulder; a spring urging said blade against said first surface when said lever is in its retracted position and being operable upon movement of said lever to its projected position for rocking said blade against said second surface for engagement with said shoulder whereby said blade and said shoulder latch said lever against returning to retracted position, said spring being yieldable when said blade is engaged by the approaching tabular stop for permitting said blade to rock and be disengaged from said shoulder to enable said normalizing means to return said lever to its retracted position; and means for disabling said escapement mechanism when said lever is moved to projected position and for re-enabling said escapement mechanism when said lever is returned to retracted position.

6. Typewriting or like machine mechanism as set forth in claim 5 in which said latch member comprises a pin and in which the mounting for said pin comprises a part fixed with respect to said frame and having an aperture through which said pin extends with radial clearance, whereby the position of said pin may be adjusted towards and away from said blade in the direction of carriage travel and towards and away from the path of said tabular stop perpendicularly to the direction of carriage travel, and means for holding said pin in adjusted position in said aperture.

7. Typewriting or like machine mechanism as set forth in claim 5 including a rebound prevent-

ing pawl mounted on said frame and being engageable with said tabular stop on the side thereof opposite that which engages said blade when said lever is in projected position; and a part on said blade engageable with said pawl for holding the latter in inoperative position when said lever is in retracted position.

8. Typewriting or like machine mechanism as set forth in claim 5 in which said normalizing means comprises a spring urging said tabular stop lever to its retracted position, and in which said actuating means comprises a power driven rotatable member, motion transmitting connections between said lever and said rotatable member including a coupler normally disengaged from said rotatable member but being movable into transient engagement therewith for momentarily coupling said rotatable member to said lever for rocking the latter to its projected position, and key mechanism for moving said coupler into such transient engagement with said rotatable member.

9. Typewriting or like machine mechanism as set forth in claim 5 in which said actuating means comprises a lever operating member connected to said stop lever, a key, and means responsive to depression of said key for imparting to said lever operating member a momentarily acting operating impulse.

10. Typewriting or like machine mechanism as set forth in claim 5 including a normally ineffective carriage brake; and means operable conjointly with movement of said stop lever to projected position and disabling of said escapement mechanism for rendering said brake effective during travel of said carriage in the typing spacing direction while unrestrained by said escapement mechanism.

11. Typewriting or like machine mechanism as set forth in claim 5 including a margin stop on said carriage; a center stop on said frame; a finger mounted for limited movement on said center stop and being disposed in the path of and being engageable by said margin stop when said carriage reaches a predetermined position in its typing spacing travel, whereby said finger is caused to have limited movement on said center stop; and means responsive to said movement of said finger for rocking said blade away from said second surface of said latch member toward said stop lever to disengage said blade from said shoulder on said latch member whereby to enable said normalizing means to restore said stop lever to retracted position.

12. Typewriting or like machine mechanism as set forth in claim 5 in which said actuating means comprises an operating member, a yieldable cushioning drive transmitting connection between said operating member and said stop lever, a key, and means responsive to depression of said key for imparting an operating stroke to said operating member.
